CARL OLAF ANDERSEN DÖVLE, OF NOTODDEN, NORWAY, ASSIGNEE TO NORSK HYDRO-ELEKTRISK KVAELSTOFAKTIESELSKAB, OF CHRISTIANIA, NORWAY.

ELECTRIC-ARC FURNACE.

1,198,116.

Specification of Letters Patent. Patented Sept. 12, 1916.

Application filed April 13, 1915. Serial No. 21,033.

To all whom it may concern:

Be it known that I, CARL OLAF ANDERSEN DÖVLE, a subject of the King of Norway, residing at Notodden, Norway, have invented certain new and useful Improvements in Electric-Arc Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to electric arc furnaces and has for its object to provide supporting means for the electrodes of such furnaces, which will make it possible to dispose the arc in any desired part of the furnace and also to permit adjustment of the electrodes so as to regulate the distance between their points viz. the length of the electric arc in accordance with the current tension and the conductivity of the gases.

25 Another object of the invention is to provide supporting means for the electrodes for polyphase furnaces which will permit a correct angular disposition of the electrodes relatively to each other.

30 The invention is adapted for metallurgical as well as for gas furnaces where an electric arc is used.

On the drawings: Figure 1 is a diagrammatical sketch of an electric arc gas furnace 35 provided with the present invention. Figs. 2, 3 and 4 are details showing several forms of electrode supports on a larger scale.

According to Fig. 1 the electrodes *a* are 40 slidably mounted in balls *b*, which rest in suitable sockets in the furnace wall. Owing to this mounting it will be noticed, that the electrodes can be approached toward each other by sliding in the bore through the ball in which they are mounted, and at the same 45 time the ball and socket joint permits angular displacement of both electrodes in different planes, so that in fact the electrode points may be placed in any convenient part of the furnace.

50 On Fig. 2 is shown a ball and socket support of the type referred to. In accordance with this form of the invention the ball *b'* is mounted between the inner spherical parts of the neck bushes *c*, *d*, which may be fastened to the furnace wall *f* in any conven-

ient manner. A packing *e* as shown may be introduced between the two neck bushes to secure a gas-tight fit. The ball piece *b'* should be made of insulating material such as porcelain, stone, glass or the like and for 60 high tension currents the neck bushes *c*, *d* should also be insulating.

According to the modification shown on Fig. 3 the part *b* in which the electrode *a* is slidably mounted is not spherical, but is 65 passed through a salient packing *e* of yielding material, which permits angular adjustment of the part *b* within certain limits. The packing *e* is supported between the two neck bushes *c*, *d*. Also in this construction the different parts of the electrode support may be made of insulating material. It will be noticed that a triple insulation 70 may be obtained if all the supporting parts are made insulating.

75 Fig. 4 illustrates the application of the present invention on a furnace in which electrodes are steadied by means of braces inside the furnace. In furnaces of this type the electrodes must be permitted to swing about their connection point with the braces inside the furnace even if such braces may also be made adjustable.

According to the construction shown on Fig. 4 the electrode *a* is supported at the 80 point *g* by means of braces *h*. The furnace wall *f* is provided with a large opening *l*, in which the electrode can move freely in all directions. A collar *m* is arranged around the opening *l* and is adapted to cooperate with a cap *n* pressed against the said collar by means of springs *h*. The cap *n* is slidably mounted on the electrode *a* and the whole arrangement forms a gas tight joint. The cap *n* and collar *m* are shown as 85 having a spherical surface, and in this way the best tightening results are obtained, but it will be understood that when the movements required are small the said parts may also be made flat, in which case the electrode 90 should be inclosed by a yielding packing on passing through cap *n*.

Claims:

1. In an electric arc furnace the combination of an electrode, means for supporting 105 said electrode inside said furnace, an opening in the furnace wall for introducing the electrode, said opening being of a larger diameter than the electrode, a collar surrounding said opening, a spherical cap slid- 110

ably mounted on said electrode and means for pressing said cap against said collar to form a gas tight joint.

2. In an electric arc furnace, an inwardly projecting support fixed to the wall of the furnace, an electrode movably mounted in the support and projecting through an aperture in said wall of larger diameter than the electrode, a collar surrounding said aperture, and a spring urged spherical cap

slidable on the collar and on the electrode, to form a gas tight joint with the collar.

In testimony that I claim the foregoing as my invention, I have signed my name in presence of two subscribing witnesses.

CARL OLAF ANDERSEN DÖVLE.

Witnesses:

M. C. GUTBOVNESLY,
C. F. HANSEN.
